UNITED STATES PATENT OFFICE

JOSEPH GILLOW GARTON, OF NEW YORK, N. Y.

DESIGN FOR A REFRESHMENT WAGON

Application filed October 24, 1932. Serial No. 45,529. Term of patent 7 years.

To all whom it may concern:

Be it known that I, JOSEPH GILLOW GARTON, a citizen of the United States, residing at New York, in the county of New York and State of New York, have invented a new, original, and ornamental Design for a Refreshment Wagon, of which the following is a specification, reference being had to the accompanying drawing, forming part thereof.

Figure 1 is a front perspective view of the refreshment wagon of my new design, showing it in the closed position, and

I claim:

The ornamental design for a refreshment wagon as shown.

JOSEPH GILLOW GARTON.
